UNITED STATES PATENT OFFICE.

THOMAS W. WILLIAMS, OF KAYLOR, PENNSYLVANIA, ASSIGNOR TO MARGARET E. WILLIAMS, OF KAYLOR, PENNSYLVANIA.

PORTABLE LADDER STEP.

Application filed February 23, 1927. Serial No. 170,317.

This invention relates to a detachable step for a ladder, the general object of the invention being to provide means for converting an ordinary ladder into a step-ladder so that the user of the ladder can stand on the step attachment in the same manner that he would use the step of a step-ladder.

Another object of the invention is to make the attachment foldable so that it will occupy but little space when not in use.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a sectional view on line 1—1 of Figure 2.

Figure 2 is a front view of portion of the ladder shown in Figure 1.

Figure 3 is a sectional view through the attachment with the same in closed position.

Figure 4 is a perspective view of the attachment in closed position.

As shown in these views, the attachment comprises a step part A and a brace part B, the step part forming a platform 1 which is fastened to the upper edges of the side pieces 2, each side piece having a notch 3 in its rear end for receiving a rung of a ladder, such as shown at C. Pins 4 are passed through holes formed in the step part to hold the rung at the rounded inner ends of the notches, as clearly shown in Figure 1.

The brace part comprises the two side pieces 5 which are pivotally connected with the front end of the step part by the rod 6 and the step forming piece 7 which connect the lower ends of the side pieces 5 together.

The upper ends of the side pieces 5 are rounded so that they will be free to move under the platform 1 and their lower ends are notched, as at 8, to receive a rung of the ladder C. The rung is held in the notches by means of the pins 9 which are similar to the pins 4. The piece 7 is set at an angle so that when the attachment is in place it will be parallel with the platform 1 or substantially so, as shown in Figure 1.

From the foregoing it will be seen that I have provided a simple arrangement of parts which, when applied to a ladder, will form two flat steps upon either one of which a person can stand while painting or performing other tasks, without discomfort as is the case when standing on the rounds of an ordinary ladder. It will also be seen that the device will adjust itself to ladders, the rounds of which are set at various distances apart and when in place, the part A is firmly held against movement by the brace part B. When the attachment is not in use, it can be folded, as shown in Figures 3 and 4, so that it can be stored in a small space.

It is thought from the foregoing description that the advantages and novel features of my invention will be readily apparent.

I desire it to be understood that I may make changes in the construction and in the combination and arrangement of the several parts provided that such changes fall within the scope of the appended claim.

What I claim is:—

Means for converting an ordinary ladder into a step-ladder comprising a step forming part including a platform and a pair of depending side pieces, one at each end of the platform, said side pieces having notches in their rear ends for receiving a rung of the ordinary ladder, a brace forming part including a pair of uprights and a single step forming strip connecting the uprights together adjacent their lower ends, said lower ends of the uprights having notches therein for receiving a rung of an ordinary ladder, the notches terminating adjacent the strip whereby the strip will rest upon the rung, a rod passing through the upper ends of the uprights and through the front ends of the side pieces for pivotally connecting the step part with the brace part, pins passing through the notched portions for connecting the parts with the rungs of the ladder, the step part being of less length than the brace part whereby the rear end of the step part can be folded between the uprights of the brace part, with the platform of greater width than the brace part whereby the platform will overlap the uprights when the device is in folded position.

In testimony whereof I affix my signature.

THOMAS W. WILLIAMS.
